COLLAPSIBLE COSTUMER

Morris Lange, Cleveland Heights, Ohio

Application October 16, 1940, Serial No. 361,423

5 Claims. (Cl. 312—173)

This invention relates to costumers or garment racks and particularly to portable, collapsible costumers suitable for use on special occasions where extraordinary crowds are likely to gather.

As conducive to a clearer understanding of this invention, it may be well to point out that on occasions such as funerals in private homes, where the facilities for accommodating garments is limited, the undertaker usually supplies a folding rack which attempts to serve the purpose. The costumers of the prior art have been cumbersome, awkward to handle, and generally occupied valuable space.

It is, therefore, the primary object of this invention to provide a collapsible costumer which folds compactly into a carrying case, which case also serves as the base of the rack.

Another object of this invention is to provide a device of this character with a novel folding hat rack.

A further object is to equip the supporting standards of such devices with folding joints that automatically snap into place and which are easy to operate.

These and other objects and features of the invention will become apparent from a study of the following description and claims together with the accompanying drawings in which like parts are designated by like reference characters and wherein:

Figure 1 is a front elevation partly in section of the costumer constituting the invention with parts of the carrying case broken away to show the construction and assembly, and showing certain parts in alternate positions illustrating the method of collapsing the device.

Figure 2 is a front view of the closed case with parts broken away to show assembly;

Figure 3 is an end view of the device in opened position taken along the lines 3—3 of the Figure 4;

Figure 4 is an elevation partly in section of the costumer illustrated in Figure 1;

Figure 5 is a view of a hat hook and support taken along the lines 5—5 of the Figure 4;

Figure 6 is a top view of an umbrella retainer taken along the lines 6—6 of the Figure 1; and

Figure 7 is a front view of a supporting member joint.

The collapsible costumer constituting this invention consists primarily of three main parts. There is first the horizontal case or container member, second, the support members, and third, the rack member. Each of these elements will

be described in detail and in the order just set forth.

The base member 10 is simply a compact carrying case having a flat bottom 11, side walls and perpendicular ends 12 thereon. The top of the case, indicated by the character 13, is provided with a carrying handle 15, and is secured to the case member 10 when in the folded or closed position by the trunk catches or fasteners 14. This lid or closure member 13 also serves as a shelf when the device is in its open or extended position.

In order to prevent the device from tipping when it is open and retaining the garments, telescoping leg supports 16 are mounted on the bottom 11. These telescoping supports 16 or extendable leg members 16 consist of channel members 17 which are rigidly attached to the bottom 11 and extend laterally thereof. An inner arm or tube portion 18, slideable within the channel or outer tube 17, extends outwardly of the sides of the case. The outer ends of the arms 18 are provided with rubber pads or feet 19. Mounted on the inside of the arm 18 is a simple spring catch 20 which engages one of the holes 21 in the bottom of the channel or tube 17. When the arm 18 is fully inside of the tube 17, the spring catch 20 engages the hole 21, and when the arm 18 is extended fully, the catch 20 similarly engages the hole 21a. There are two support elements adjacent to each end of the bottom 11. One arm on each end extends outwardly to the left, and one arm 18 on each end extends outwardly to the right, so that when the four arms are extended fully, the base of the costumer stands on an area almost twice the area of the case bottom 11.

The inside of the case 10 is partitioned off into compartments which are suitable for containing a number of coat hangers 55, and two umbrella holders 50. These will be described in detail hereinafter. In the drawings, the longitudinally extending partition 23, together with the side wall of the case, forms a compartment 40 for retaining the umbrella holders 50, and similarly, the partition 24, together with its neighboring wall, forms a compartment for retaining a supply of coat hangers 55.

The frame or collapsible support members for the device consist of vertical, tubular uprights 30 and 31, hinged together at the joints 46 which when in the extended condition are perpendicular to the bottom member 11. The lower tubular supports 30 are a little shorter than the length of the base 11. These are attached to

the base 11 so that when folded inward or toward each other, the supports 30 fit into the case and are parallel to the base 11 when in a folded condition. In Figure 1 of the drawings, there is shown in broken lines the manner of folding the supports into the carrying case; and Figure 2 shows the vertical supports completely folded therein. A bracket member 32, which is simply a length of U shaped metal commonly referred to as a channel iron, is attached to the base 11 on the inside of the case about midway between the two long side walls and quite close to the end walls 12. These brackets 32 extend longitudinally of the case. Immediately above the brackets 32 and attached to the end walls 12, are vertical brackets 33 which have substantially the same shape and size as the previously described horizontal brackets 32. Two spaced triangular plates 34 are fastened to and connected with the side walls of the channelled brackets 32 and 33. The vertical supports 30 are pivotally connected by means of the horizontal pin 34 to the parallel triangular plates 34 as shown in the Figures 3 and 4. Mounted on the pin 34 and engaging the support 30 is a spring 35, the tension of which urges the supports 30 to an upright or vertical position. This construction and spring 35 is clearly shown in Figures 3 and 4. The brackets 32 and 33 are also referred to herein as stabilizing means for the reason that when the supports 30 are folded into the case, they fit into the open or channel portion of the brackets 32 and are held rigid and firm in the case. Similarly, when the supports 30 are fully opened, they are engaged by the vertical brackets 33 and they are then held in rigid engagement with the end walls 12.

The upper support members 37 are just a little shorter than the lower support members 30, so that they too might conveniently fit into the closed case.

The two support members 30 and 37 have a unique connection means. This joint 40 can, when the device is opened, retain the members 30 and 37 in rigid vertical alignment. For this purpose there is provided a fixed collar 41, which is firmly attached to the lower support 30. This collar has an inside diameter sufficient to receive the upper support 37 and is open on its outer side so as to permit free pivotal movement of the upper support 37. The upper support 37 has a hinge member 42 attached thereto, which hinge member engages the fixed collar 41 by means of the hinge pin 43.

Slightly above the hinge 42 there is mounted a slidable collar 44 on the upper support member 37. This slidable collar 44 is provided with a tongue or clip 48, which engages the fixed collar 41 when the two supports 30 and 37 are in perfect alignment. This slidable collar 44 is held downward so that the tongue 48 engages the fixed collar 41 by a spring 45, which is inside the tubular support 37. The lower end of the spring 45 is attached to the tab or ear 46 on the support 37, and is attached to the slidable collar 44 by means of the pin 47. This pin 47 is rigidly attached to the collar 44 and passes through a curved slot or hole 49 in the upper support member 37. The tension of the spring 45 urges the collar downward. By simply rotating the slidable collar 44 in either direction, the pin 47 rides the curved slot 49 so that the tongue 48 is raised sufficiently to disengage the upper edge of the fixed collar 41. When the slidable collar 44 is so rotated, the supports 30 and 37 may be easily folded.

The lid member or cover 13, heretofore referred

to as a top horizontal portion, indicated by the character 80 in the drawings, serves as a shelf for hats, packages, etc. Extending downwardly from the shelf portion 80 and just a little inside the ends thereof, are two Y shaped brackets 61. The top end of the vertical support 37 is hingedly connected to the lower end of the bracket 61 so that the support member 37 may fold inward when the device is collapsed. A simple hinge pin 62, which engages the top end of the support 37 and the lower end of the bracket 61, is provided for this purpose. Slightly above the top of the supports 37 and attached to the two brackets 61, there is a bar member and particularly a tubular rod 63 which extends longitudinally and horizontally under the shelf 80. This tubular rod 63 is included to provide a convenient means for holding the coat or garment hangers 65. In order to provide extra room for so supporting the garment hangers 65, extension or telescoping members 64 are inside of the tube 63. These extension members 64 may be withdrawn by grasping the handle or knob 65 on the outer surface of the brackets 61. The Figure 1 of the drawings shows the extension bars 64 drawn out to provide extra hanging space; and the Figure 4 shows the bars 64 in the collapsed position which permits it to be received by the case 10.

The hat hangers 66 of which there are six projecting outwardly on each side of the device, are attached to a length of angle iron 67. The ends of these lengths of iron 67 are pivoted to the ends 12a of the lid member 13 as indicated by the pivot pins 68 in the drawings. This permits the hat hangers 66 to be extended or placed in a substantially horizontal position when the costumer is opened for use, or they may be turned downward so as to fit into the carrying case 10 when the device is collapsed. The Figure 3 of the drawings shows how the hat hangers 66 may be either opened or closed. In order to retain the hat hangers 66 and the angle iron 67 in a firm or rigid open position, there is provided a catch member 69. This is simply a small lever 69 pivoted to the bracket 70 and mounted on the lid member 13, so that the notch 72 in the lever 69 engages an edge of the angle iron 67. The small spring 71 urges the catch 69 into engagement therewith.

Two umbrella supports are provided for the device. These are simply water-proof bags 50 which fit on and hang from the semi-circular frame 51. The frame 51 may be made of wire bent as shown in the Figure 6 with a small hook 53 at its middle, which fits into the holes 52 of the support members 30 and are held in place thereby.

To set up the costumer, the user first draws the arms 18 out of the channelled tubes 17 as far as they will go in order to extend the base. The snaps or locks 14 are unfastened and the lid 13 lifted vertically as far as it will go. This lifting operation automatically straightens the vertical supports 30-37, and when perfectly straight, the joints 40 will snap into place holding the supports rigid. The two horizontal rods 64 are withdrawn from the tube 63 as far as they will go; and then the hooks 66 are swung outward and upward until firmly held in place by the spring members 69 and finally, if necessary, the bags 50 are hung on the vertical supports 30 as shown in the Figure 1. When closing the device, the aforesaid operations are simply reversed.

It will now be clear that there is provided by

this invention a collapsible costumer which accomplishes the objects of the invention. While the invention has been disclosed in its preferred form it is to be understood that the embodiment of the invention as described and illustrated herein is not to be considered in a limited sense as there are many other forms or modifications of the invention which are also considered to be within the scope of the appended claims.

I claim:

1. A collapsible costumer, comprising in combination, a container having a bottom and side walls, collapsible support members hingedly mounted in the container and being perpendicular to the said bottom when in an extended position and parallel thereto when in a folded condition, a bar member mounted on the support members receivable by the container when the support members are in the folded condition, and a lid member having a plurality of hooks thereon mounted on the bar member and closing the container when the support members are collapsed and in the folded condition.

2. A collapsible costumer of the type defined in claim No. 1, and further characterized by the said hooks being foldable and receivable by the container when the support members are in the folded condition and extendable outwardly of the lid member when the said support members are in the extended position.

3. A collapsible costumer, comprising in combination, a container having a bottom and side walls, collapsible support members hingedly

5 mounted in the container and being perpendicular to the said bottom when in an extended position and parallel thereto when in a folded condition, and a lid member mounted on the support members and closing the container when the support members are collapsed and in the folded condition, the said lid member having a plurality of foldable hat hooks thereon extending outwardly when the costumer is extended and being receivable by the container when the costumer is folded.

10 4. A collapsible costumer of the type defined in claim No. 3, and further characterized by the lid member having a horizontal bar depending therebelow.

15 5. A collapsible costumer, comprising in combination, a container having a bottom portion and side walls, collapsible support members hingedly mounted in the container and being perpendicular to the said bottom when in an extended position and parallel thereto when in a folded condition, a lid member mounted on the support members and closing the container when the support members are collapsed and in the folded condition, the said lid member having a plurality of foldable hat hooks thereon extending outwardly when the costumer is extended and being receivable by the container when the costumer is folded and extendable leg members 20 30 mounted on the said bottom portion retaining the aforesaid members upright when in the extended position.

MORRIS LANGE.
